UNITED STATES PATENT OFFICE.

LOUIS JAY GERSON, OF PALISADES, NEW YORK.

PHONOGRAPH CABINET.

Application filed October 10, 1919, Serial No. 329,830. Renewed January 14, 1922. Serial No. 529,372.

To all whom it may concern:

Be it known that I, LOUIS JAY GERSON, a citizen of the United States, residing at Palisades, in the county of Rockland and 5 State of New York, have invented certain new and useful Improvements in Phonograph Cabinets, of which the following is a specification.

This invention relates to phonograph cab-

10 inets, the object of the invention being to provide a knock-down metal cabinet, simple in construction and comparatively inexpensive to manufacture whereby the cabinet may be shipped in a knock-down condition 15 and readily assembled by the dealer or user, so that many such cabinets may be shipped in a freight car as compared with the number which it has heretofore been possible to ship in such a car.

20 In the present improvement the cabinet is made entirely of metal and is so constructed that all the parts thereof may be readily assembled without the use of rivets or other similar fastening means whereby the dealer 25 or user can quickly and easily assemble the several parts expeditiously.

The cabinet is so constructed of metal that upon its proper assemblage there will be no rattling or vibration of the several parts 30 which go to make up the cabinet, and in which but four connecting bolts are used to connect the several members.

In the drawings accompanying and forming a part of this specification, Fig. 1 illustrates this improved cabinet properly assembled; Fig. 2 is a cross section of the cabinet taken below the horn; Fig. 3 is a vertical section taken on line 3—3 of Figure 2; Fig. 4 is an enlarged sectional view of one corner 40 of the cabinet taken on line 4—4 Figure 3; Fig. 5 is a sectional view of one corner of the cabinet taken on line 5—5 Figure 2; Fig. 6 is a perspective view of the door panel of the cabinet; Fig. 7 is a perspective view of 45 one of the doors; Fig. 8 is a perspective partly sectional view of the top of the cabinet; Fig. 9 is a perspective view of the motor supporting shelf or member of the cabinet; Fig. 10 is a detail sectional view of the 50 top shown in Figure 8; Fig. 11 is a perspective view of the metal horn; Fig. 12 is a perspective view of one of the corner members or posts; Fig. 13 is a perspective view of one of the side or back panels of the cabinet; Fig. 14 is a perspective detail view partly 55 broken away by one of the shelves of the

cabinet; Fig. 15 represents detail views of the spacers between the shelves; Fig. 16 illustrates one of the four bolts used in connecting the several parts together; Fig. 17 60 is a perspective view of the caster supporting member attachable to the corner posts; and Fig. 18 is a detail view illustrating the manner in which the horn is supported on the motor support board. 65

Similar characters of reference indicate corresponding parts in the several figures of the drawings.

This improved cabinet is made up of metal members so constructed that they may be 70 readily assembled without the use of rivets or other similar fastening means, and for this purpose four specially constructed posts or corner members 2 are provided. Each of these corner members is shown as rectangular in form and is provided along one edge thereof with inturned flanges 3 forming a pair of U-shaped channels 4 for the reception of the front, side and back panels 5 and 6, each of which has its side edges so bent or 75 folded as at 7 that when inserted downwardly from the top of said posts or corner members they will receive the bent flanges 3 of such corner members in the manner shown in Fig. 4, the folded portions of the panels 80 overlapping the channel-formed portions of the corner posts whereby such panels may be readily dropped into place in the posts or the posts inserted on the panels, the position of the panels being determined by suitable 85 inturned portions 8 of the posts (see Fig. 12). It will be observed that the posts and panels are independent of each other and that each post has a pair of right angle sides, each side terminating in a pair of 90 right angle bent portions, which thus form the U-shaped channels 4, and that each panel has each upright edge thereof bent upon itself and spaced apart to form two pair of 95 angular lapping portions, one pair located at 100 an angle to the other, and which two pair of lapping portions overlap, as hereinbefore stated, a channel-formed portion of the post and interlock therewith. This construction of the right angle overlapping spaced-apart portions at each edge of a panel it will 105 be observed (see Fig. 4) enables the panel to be ornamenteally formed by projecting the center part thereof beyond the edges and still have such center part in line if desired 110 with one side of the post. In other words, this formation at the edge of the panel en-

ables the panel itself to be panel-shaped, as it were. Each panel 5 and 6 is provided with an inturned flange 9 for the reception of a suitable shelf or bottom 10 upon which flanges the bottom may rest. A bottom 10 and suitable shelves 11 are provided, each having its four corners so formed or cut as at 12 that they will fit into the hollow corner members or posts 2 and for this purpose each corner of the shelf is provided with a pair of L-shaped slots 13 forming an angular or L-shaped corner 14 corresponding to the shape of the corner post 2 whereby when the shelves are dropped into position in the corner posts they will accurately fit therein so that the flanges 3 of the corner post and folded parts 7 of the panels will be received in the L-shaped slots 12 of the shelves. The shelves are maintained apart by suitable spacers 15 and 16, one of each being in the form of tubes and the other in the form of ogee corner members adapted to overlap the edges of the panels 7 (see Fig. 4) whereby the shelves are maintained in their proper position when inserted in the posts. A suitable caster 17 provided with a supporting member or block 18 is provided to insert in the lower end of each post 2, the block being provided with a bolt hole for the reception of the bolt hereinafter mentioned. By the term "caster" as herein used, is intended to mean any suitable device which facilitates the movement of the cabinet over the floor. A motor supporting platform or base 19 is provided and this platform is furnished with a flange 20 adapted to fit on to the upper edge of the four side walls or panels, which latter may be given any suitable shape or formation to provide any desired ornamentation. This platform is provided with an opening 21 within which to hang the motor and suitable ears 22 to carry the motor board, which may be hinged to the ears by suitable pivots. The platform 19 is also provided with a pair of inwardly extending flanges 23, which flanges are located below the side walls 24 of the platform, and in position to receive the flange 25 of the metal horn or amplifier when such is used 26 so that by this means the horn may be readily slipped into place and secured without the use of rivets or bolts. The top of the cabinet 27, which may be of any suitable formation adapted to be pressed from metal, is shown in the present instance as made of two members 28 and 29 suitably connected by the beading or overlapping of the edges thereof, and is adapted to rest upon the top of the motor supporting platform 19 and to be hinged to the rear panel in any suitable manner. The front panel may be provided with one or more doors or sets of doors as 30 and 31, one for instance to permit ingress to the several shelves of the cabinet and the other to open and close the mouth of the horn if desired. Each of these doors is provided with a suitable bent edge 32 for the reception of a pintle or pivot pin 33, which is adapted to pass through inwardly turned flanges 34 and 35 formed as a part of the jamb of the door in the front panel, and each pair of doors may be provided with suitable fastening means or knobs for securing them in position and manipulating them. The usual rotary table 40 and sound-producing means 41 is provided and attached as shown in Fig. 3. In the construction of the several parts in the manner hereinbefore described, the motor supporting base 19 is provided at each corner thereof with a bolt hole 19^a for the reception of the bolts about to be mentioned.

In assembling the several parts of this improved cabinet, the sides or side panels and the bottom and shelves are slipped into position in the manner hereinbefore described; then the supporting base 19 is placed in position, and then a bolt 45 is located adjacent to each corner post, passing through an opening as 12^a in each shelf, through the spacer members 15, through the lower part of each post and threaded into the opening in the caster block or therethrough for the reception of a nut, whereby the panels and shelves and casters are all firmly connected together, the adjacent edges of the panels where they engage the corner post being suitably spaced apart by the spacers 16, the ogee edges of which overlap the folded edges of the parts 7 of the panels. These spacer members are shown formed of sheet metal and consequently have a certain amount of resiliency whereby they maintain the spaced lapping portions of a pair of panels into proper tight engagement with the posts and prevent rattling, while it will also be observed that the two pair of spaced lapping portions located at an angle one to the other of the panel materially assist in preventing movement of the panel in transverse directions. In practice a suitable anti-vibration means, such as asbestos or sawdust may also be inserted into the corner posts between the shelves and above the upper shelf to fill the corner posts and thereby prevent rattling and vibration of the connected parts.

One of the side panels is provided with the usual opening as 50 (see Fig. 1) for the insertion of the usual crank handle to wind the motor when this form of motor is provided. Thus it will be observed from the foregoing, that by the use of four bolts, the four panels, four corner posts, the bottom, the motor supporting board or platform and any desired number of shelves, may be all rigidly and quickly assembled so that the several parts may be readily struck up or pressed from metal such as sheet metal and a very rigid, compact and comparatively inexpensive knock-down

metal phonograph cabinet provided, in which there is no warping or shrinkage or expansion of the several parts to interfere with the proper assemblage of the parts, and that the structure may be readily shipped in its knock-down condition so that a great many more may be shipped in a freight car than is the case where as heretofore these cabinets had to be shipped completely assembled.

I claim as my invention:

1. A completely enclosed knock-down metal cabinet comprising corner posts and side panels, one having a pair of right angle sides, each side terminating in a pair of right angle bent portions, and the other having its upright edges each bent upon itself and spaced apart to form two pair of lapping portions one pair located at an angle to the other interlocking with a pair of right angle portions of its companion part.

2. A completely enclosed knock-down metal cabinet comprising corner posts, each having a pair of right angle sides, each side terminating in a pair of right angle bent portions, spaced apart, and side panels projecting through the spaces formed in said posts and each having its upright edges each bent upon itself and spaced apart to form two pair of lapping portions one pair located at an angle to the other the spaced-apart portions of the panels receiving the right angle bent portions of the posts.

3. A completely enclosed knock-down metal cabinet comprising corner posts and side panels, one having a pair of right angle sides, each side terminating in a pair of right angle bent portions and the other having its upright edges each bent upon itself and spaced apart to form two pair of angular lapping portions interlocking with a pair of right angle portions of its companion part, and one or more shelves having opposed angular slots interlocked with said corner posts.

4. A completely enclosed knock-down metal cabinet comprising independent corner posts and side panels, each having bent interlocking portions, a pair of side panels projecting into each corner post, a bottom, one or more shelves also interlocked with said panels and corner posts, a motor supporting portion, and a single bolt projecting through a part of each post for holding all of said parts interlocked.

5. A completely enclosed knock-down metal cabinet comprising corner posts, each having a pair of right angle sides, each side terminating in a pair of right angle bent portions spaced apart side panels projecting through the spaces formed in said posts and each having its upright edges each bent upon itself and spaced apart to form two pair of angular lapping portions, the spaced-apart portions of the panels receiving

the right angle bent portions of the posts, and one or more shelves having opposed angular slots interlocked with the bent portions of the panels and corners posts.

6. A completely enclosed knock-down metal cabinet comprising four corner posts having spaced-apart bent inner edges, four panels having bent overlapping portions interlocking with the bent edges of the posts, and one or more shelves having slotted corners, the slots receiving the bent edges of the panels and interlocking therewith.

7. A completely enclosed knock-down metal cabinet comprising four corner posts having spaced-apart bent inner edges, four panels having bent overlapping portions interlocking with the bent edges of the posts, one or more shelves having slotted corners, the slots receiving the bent edges of the panels and interlocking therewith, each of said shelves also having a bolt opening therethrough and a bolt extending through the shelves and a part of a post for holding the parts assembled.

8. A completely enclosed knock-down metal cabinet comprising corner posts having spaced-apart bent edges, side panels having bent overlapping portions interlocking with said bent edges, a pair of panels interlocking with each post, and one or more shelves having opposed angular slots for insertion into such corner posts, the slots receiving a pair of bent overlapping parts of a pair of panels.

9. A completely enclosed known-down metal phonograph cabinet comprising corner posts, side panels having bent overlapping and interlocking portions; one or more shelves having opposed slots for insertion into such corner posts, a motor supporting portion adapted to partly fit within the panels and be supported thereby, and a bolt extending through such motor supporting portion, the shelves and a part of a corner post for holding all of such parts together.

10. A completely enclosed known-down metal phonograph cabinet comprising corner posts, side panels having bent overlapping and interlocking portions, one or more shelves having opposed slots for insertion into such corner posts, a motor supporting portion adapted to partly fit within the panels and be supported thereby, a bolt extending through such motor supporting portion, the shelves and a corner post for holding all of such parts together, resilient spacing members for holding such shelves apart having bent edges overlapping the bent edges of the panels, and spacing members for holding the interlocking portions of the posts and side panels apart.

11. A completely enclosed knock-down metal phonograph cabinet comprising corner posts, side panels having bent overlapping and interlocking portions, one or more

shelves having opposed slots for insertion into such corner posts, a motor supporting portion adapted to partly fit within the panels and be supported thereby, a bolt extending through such motor supporting portion, the shelves and a corner post for holding all of such parts together, spacing members for holding such shelves apart, and spacing members for holding the interlocking portions of the posts and side panels apart, said motor supporting portion having guideways for the reception of a horn.

12. A completely enclosed knock-down metal phonograph cabinet comprising hollow corner posts, side panels, the corner posts and panels having bent overlapping and interlocking portions, caster supporting means adapted for insertion into the lower ends of the posts, one or more shelves having interlocking portions adapted to fit into the posts, a motor supporting portion, and bolts adapted to pass through said motor supporting portion, the shelves, a part of the corner posts and into the caster supporting portion, one bolt for each corner post thereby to hold the several interlocking parts together.

13. A completely enclosed knock-down metal phonograph cabinet comprising hollow corner posts, side panels, the corner posts and panels having bent overlapping and interlocking portions, caster supporting means adapted for insertion into the lower ends of the posts, one or more shelves having interlocking portions adapted to fit into the posts, a motor supporting portion, bolts adapted to pass through said motor supporting portion, the shelves, a part of the corner posts and into the caster supporting portion, one bolt for each corner post thereby to hold the several interlocking posts together, one of the side panels having one or more doors having bent hinged portions and secured to the panel by an insertable pivot pin, said motor supporting portion having ways for the sliding attachment of a horn.

14. A completely enclosed knock-down metal cabinet comprising a hollow corner post having inturned flanges extending along the major portion thereof and forming U-shaped spaced-apart portions, and side panels, each having each upright edge bent to provide two pair of spaced angular lapping portions, one pair located at an angle to the other, said lapping portions adapted to receive and interlock with the bent portion of a corner post.

15. A completely enclosed knock-down metal cabinet comprising a hollow corner post having inturned flanges extending along the major portion thereof and forming U-shaped spaced-apart portions, and side panels, each having each upright edge bent to provide two pair of spaced angular lapping portions, one pair located at an

angle to the other, said lapping portions adapted to receive and interlock with the bent portion of a corner post, said corner post having means for limiting the downward movement of the panels.

70

16. A completely enclosed knock-down metal cabinet comprising a hollow corner post having inturned flanges extending along the major portion thereof and forming U-shaped spaced-apart portions, side panels, each having each upright edge bent to provide two pair of spaced angular lapping portions, one pair located at an angle to the other, said lapping portions adapted to receive and interlock with the bent portion of a corner post, and resilient spacer members having ogee portions for holding the bent side edges of a pair of panels.

75

17. A completely enclosed knock-down metal phonograph cabinet comprising a hollow corner post having inturned flanges extending along the major portion thereof and forming U-shaped portions, side panels, each having its edge bent to provide an L-shaped portion adapted to receive and interlock with the bent portion of a corner post, spacer members for holding apart the bent side edges of a pair of panels, and one or more shelves, each having a pair of opposed L-shaped slots forming interlocking means with the corner posts.

80

18. A completely enclosed knock-down metal phonograph cabinet comprising a hollow corner post having inturned flanges extending along the major portion thereof and forming U-shaped portions, side panels, each having its edge bent to provide an L-shaped portion adapted to receive and interlock with the bent portion of a corner post, spacer members for holding apart the bent side edges of a pair of panels, one or more shelves, each having a pair of opposed L-shaped slots forming interlocking means with the corner posts, means for spacing the shelves apart, and a motor supporting flanged member adapted to overlap the tops of said panels and posts.

90

19. A completely enclosed knock-down metal phonograph cabinet comprising a hollow corner post having inturned flanges extending along the major portion thereof and forming U-shaped portions, side panels, each having its edge bent to provide an L-shaped portion adapted to receive and interlock with the bent portion of a corner post, spacer members for holding apart the bent side edges of a pair of panels, one or more shelves, each having a pair of opposed L-shaped slots forming interlocking means with the corner posts, means for spacing the shelves apart, a motor supporting flanged member adapted to overlap the tops of said panels and posts, a caster supporting member adapted for insertion into the lower hollow ends of said posts, and a single bolt

for each post adapted to pass through the motor supporting member, the shelves and a part of its post and into the caster supporting member for holding the parts interlocked.

20. A completely enclosed knock-down metal phonograph cabinet comprising a hollow corner post having inturned flanges extending along the major portion thereof and forming U-shaped portions, side panels, each having its edge bent to provide a portion adapted to receive and interlock with the bent portion of a corner post, spacer members for holding apart the bent side edges of a pair of panels, one or more shelves, each having a pair of opposed L-shaped slots forming interlocking means with the corner posts, means for spacing the shelves apart, a motor supporting flanged member adapted to overlap the tops of said panels and posts, a caster supporting member adapted for insertion into the lower hollow ends of said posts, a single bolt for each post adapted to pass through the motor supporting member, the shelves and a part of its post and into the caster supporting member for holding the parts interlocked, said motor supporting member carrying a motor board and also having guideways for the sliding attachment of a horn, a metal formed top hinged to one of said side panels, one of said side panels having inturned jamb flanges for the reception of a door pintle, and a door having a bent edge adapted to receive said door pintle.

21. A completely enclosed knock-down metal phonograph cabinet comprising a hollow corner post having inturned flanges extending along the major portion thereof and forming U-shaped portions, side panels, each having its edge bent to provide an L-shaped portion adapted to receive and interlock with the bent portion of a corner post, spacer members for holding apart the bent side edges of a pair of panels, one or more shelves, each having a pair of opposed L-shaped slots forming interlocking means with the corner posts, means for spacing the shelves apart, a motor supporting flanged member adapted to overlap the tops of said panels and posts, a caster supporting

member adapted for insertion into the lower hollow ends of said posts, a single bolt for each post adapted to pass through the motor supporting member, the shelves and a part of its post and into the caster supporting member for holding the parts interlocked, said motor supporting member carrying a motor board and also having guideways for the sliding attachment of a horn, a metal formed top hinged to one of said side panels, one of said side panels having inturned jamb flanges for the reception of a door pintle, and a door having a bent edge adapted to receive said door pintle.

22. A completely enclosed metal shelf for a phonograph cabinet having at each corner thereof a pair of spaced-apart opposed L-shaped slots forming a portion adapted to project into a corner post.

23. A completely enclosed metal shelf for a phonograph cabinet having at each corner thereof a pair of spaced-apart opposed L-shaped slots forming a portion adapted to project into a corner post, and also having adjacent to said slots a bolt opening.

24. A completely enclosed side panel for a phonograph cabinet having each side edge thereof bent upon itself to form two pair of spaced lapping portions, each pair bent at right angles to its companion pair.

25. A completely enclosed motor supporting top for a phonograph cabinet having an outwardly flanged edge, having in each corner thereof a bolt opening and provided with ways for the reception of a horn.

26. A completely enclosed motor supporting top for a phonograph cabinet having an outwardly flanged edge, having in each corner thereof a bolt opening and provided with ways for the reception of a horn, said motor supporting top also having an opening, and ears for the reception of a hinged member.

Signed at Palisades in the county of Rockland, and State of New York, this first day of October, 1919.

LOUIS JAY GERSON.
